CAPACITY ALARM SYSTEM

Charles K. Roberts, Canton, Ohio, assignor to Diebold, Incorporated, Canton, Ohio, a corporation of Ohio
Filed June 2, 1959, Ser. No. 817,517
3 Claims. (Cl. 340—258)

The invention relates to an electronic capacitance alarm system or device for protecting specific objects, such as money chests, safes, record files, metal desks, open areas, fences, etc.; and more particularly to a burglar alarm system of the capacitance type with which the approach of an intruder to the immediate location of the protected object or contact of an animate or inanimate object with the protected object actuates a signal, alarm, or other selected device or equipment.

Many prior capacity alarm devices have been known or used which generally include in the protective system a signal means connected with the protected object so that the protected object serves as an antenna. The signal means in such prior systems or the protected object, or both, are connected to a monitor means which actuates an alarm means.

Various difficulties have been encountered in the operation and use of all known prior capacity alarm devices. Thus it has been possible with prior systems for an intruder to take some step or to perform some act—commonly called a "defeat" measure—which will render the system inoperative to give an alarm of the presence of the intruder.

Certain prior devices have been so constructed as to prevent defeat measures from being applied to the signal means or to its line connection with the protected object. However, no prior known capacity alarm system has been characterized by the inability to apply defeat measures to the line or communication between the signal means or protected object and the monitor means.

Furthermore, prior capacity alarm systems have been complicated in design and construction, have been difficult to adjust and maintain in adjustment in use, and some have been subject to malfunctioning by changes in atmospheric or weather conditions.

Accordingly, it is a general object of the present invention to provide a capacity alarm system or device of improved construction and operation as compared with prior known systems and which is completely transistorized with controllable sensitivity, which has reliability, and which overcomes all known faults and avoids difficulties experienced in the use of prior known systems or devices.

Furthermore, it is an object of the present invention to provide an improved capacity alarm device which not only protects the specific protected object but also protects all of the various elements of the alarm device from defeat.

Also, it is an object of the present invention to provide an improved capacity alarm device which has a very simplified and inexpensive construction from the standpoint of circuitry and circuitry elements, which is simple to set up, install, adjust and operate, which may be readily adjusted for sensitivity, which is unaffected in operation by changes in atmospheric or weather conditions, and which is reliable in use.

Furthermore, it is a specific object of the present invention to provide a new capacity alarm device which is completely transistorized with the use of only one transistor.

Also, it is another object of the present invention to provide an improved capacity alarm device in which only one wire is utilized to connect the signal means with the

2

monitor means, and in which the alarm device protects this single wire as well as the protected object.

Furthermore, it is an object of the present invention to provide an improved, transistorized, self-protected capacity alarm device which when once adjusted upon installation requires no further adjustment during continued operation and use for long intervals of time.

Furthermore, it is an object of the present invention to provide an improved capacity alarm device which cannot be defeated by any known defeat measures heretofore capable of use to defeat prior systems.

Also, it is an object of the present invention to provide the improved capacity alarm system and device with accessory controls which enable the system per se, housed in a cabinet, to be protected against tampering at all times, even though the system is disconnected from the protected object for authorized use of the protected object, as in the day time.

Finally, it is an object of the present invention to provide an improved capacity alarm device which overcomes existing difficulties in the art, solves existing problems in the art, and obtains the foregoing objectives and desiderata in a simple and inexpensive manner.

These and other objects and advantages apparent to those skilled in the art from the following description and claims may be obtained, the stated results achieved, and the described difficulties overcome, by the systems, devices, apparatus, constructions, elements and arrangements which comprise the present invention, the nature of which is set forth in the following statement, preferred embodiments of which—illustrative of the best modes in which applicant has contemplated applying the principles—are illustrated in the drawings and set forth in the following description, and are particularly and distinctly pointed out and set forth in the appended claims forming part hereof.

In accordance with the invention, a transistorized RF oscillator circuit, preferably of the tickler feedback regenerative design, which may be simply called the signal means, supplies energy through a line connected with the protected object, such as a safe and the like, acting as an antenna, to establish a field of electromagnetic radiation or RF energy around the protected object and the line connected between the protected object and signal means.

A single line also connects the signal means with a monitor means, which, in turn, actuates an alarm means. A field of electromagnetic energy supplied from the signal means also is established around this single line connection between the signal means and monitor means. As any object moves into or out of the fields of radiation thus established around the protected object and the line connected therewith as well as the single line connected between the signal means and monitor means, the monitor means detects such movement and actuates the alarm means.

By way of example, the improved capacity alarm device is shown somewhat diagrammatically in the accompanying drawings forming part hereof, wherein:

FIGURE 1 shows one arrangement of improved capacity alarm system including details of a signal means connected to the protected object and to a monitor means, the latter of which actuates an alarm means;

FIGURE 2 is a perspective view of a cabinet with the door closed, housing components of the improved capacity alarm device;

FIGURE 3 is a view similar to FIGURE 2 but showing the cabinet door open;

FIGURE 4 is a fragmentary wiring diagram illustrating an automatically compensated tamper switch which may be added to the capacity alarm system of FIG. 1 as an additional control device for the system;

FIGURE 5 is a fragmentary enlarged view of the meter relay incorporated in the system of FIG. 1 equipped with a reset control operating cam positioned in "Day" or non-security position;

FIGURE 6 is a view similar to FIG. 5 showing the cam passing through its reset position upon movement from "Day" to "Night" position, or vice versa; and,

FIGURE 7 is a view similar to FIGS. 5 and 6, but showing the cam in "Night" or security position.

Similar numerals refer to similar parts throughout the various figures of the drawings.

The capacity alarm system shown includes a combination of major circuit components. The object to be protected, herein termed the "protected object," may be a safe generally indicated at 1 or any other metallic object, such as a money chest, a record file, a metal desk, a fence and the like. The improved capacity alarm system is intended primarily for the protection of such specific object and the atmosphere, zone or area immediately surrounding the protected object such as, for example, within one, two or three feet of such protected object. The safe 1, or protected object, preferably rests on some insulating material to electrically insulate the object from the ground to obtain maximum sensitivity for the system, but the protected object 1 need not be so insulated.

The protected object 1 is connected by a single wire line 2 at point 3 into the electrical circuit of a signal means generally indicated at 4. The signal means circuit 4 comprises generally lines 5, 6, 7 and 8 and related components including battery 9 or power supply and transistor 10. The signal means 4 comprises a transistorized RF oscillator circuit, of known tickler feedback regenerative design, supplying RF energy at the collector 11 of transistor 10 and at point 3 to which collector 11 is electrically connected.

When the system is in operation a field of RF energy is established around wire 2 and the protected object 1 acting as an antenna, this field of electromagnetic radiation drawing energy from the transistorized RF oscillator circuit comprising signal means 4.

In accordance with the invention, a single wire 12 also connects point 3 with a monitor means generally indicated at 13 comprising a monitoring circuit. The monitor means 13 actuates an alarm means generally indicated at 14. In accordance with the invention, a field of RF energy is also established around the single line wire 12 connected between the signal means and monitor means.

When the system is placed in operation, an electromagnetic energy balance is reached as the field is saturated around the protected object 1 (serving as an antenna) as well as around single wire 2 and single wire 12 and no additional energy is drawn from the oscillator circuit or signal means 4 other than that required to sustain the field. As any object moves within or into or out of this established field of radiation it will either absorb energy and create a greater demand on the oscillator circuit of the signal means, or reduce the field and lessen the required potential that previously existed. Since the system depends upon a difference above ground, greater sensitivity may be obtained if the protected object is insulated from the ground.

The self-balancing monitor means 13 monitors the energy potential available at the oscillator circuit or signal means with respect to the static field, and initiates an alarm if a change greater than a preselected amount occurs, such as, for example, plus or minus two micro-amperes.

Single wire 12 is connected through capacitor 15 with monitor means 13 at point 16 between a pair of diodes 17a and 17b to rectify the RF energy into direct current. A series capacitor 18, a Wesson sensitive relay 2-0-2 micro-ampere sensitrol 19 and a resistor 20 shunting the capacitor 18 and relay 19, together with a capacitor 21

from the positive side of diode 17a to the ground at 22, complete the circuit of monitor means 13.

As the oscillator of signal means 4 charges the magnetic field, the rectified current is applied to charge capacitor 18 in the circuit of monitor means 13. As the electromagnetic field becomes saturated, a fixed voltage and current balance is reached in the monitor means circuit. The series capacitor 18 reaches this level, current ceases to flow in the monitor means circuit and the Wesson relay 19 will balance with indicator 23 thereof at the zero position.

Any change of the oscillator energy in the oscillator circuit of signal means 4 results in current flow in one direction or the other in the monitor circuit of monitor means 13, and, in turn, results in either a positive or negative swing of the Wesson relay indicator 23. This indicates that the series capacitor 18 is absorbing more charge or discharging its energy through the shunting resistor 20.

A control circuit for the alarm means 14 consists of wire 24 from the + side of main power battery 9, through bell test button 25, resistance 26, resistance 27, blade 28 of relay 29 (normally closed when de-energized), wire 30, wire 31, coil 32 of bell 33, armature coil 34 of alarm means relay 35 whose blade 36 is normally in upper position when the relay is energized, wire 37 and wires 6 and 7 to the - side of battery 9. This control circuit normally holds relay 35 energized, with its blade 36 normally open. The resistances 26 and 27 reduce the current flow to an amount insufficient to operate the bell, though the circuit for energizing relay 35 passes through the coil 32 of bell 33.

The bell test button 25 is normally closed to maintain the control circuit for the alarm means 14 energized so that alarm means relay 35 is energized with its blade 36 in the open position shown. When the bell test button 25 is actuated to test operation of the bell 33, it opens the control circuit for the alarm means 14 and thus de-energizes alarm means relay 35 which permits the relay blade 36 to drop to the position 36a shown in dot-dash lines. The dot-dash line position 36a of blade 36 closes the alarm circuit of alarm means 14 completed from battery 38 through wire 39, bell coil 32, wire 31, wire 40, blade 36a, and wire 41 to battery 38, energizing the bell 33. The bell if functioning, thus rings when bell test button 25 is actuated to determine whether bell is operative. After release of the bell test button 25, for test purposes, the control circuit for the alarm means 14 is again energized, energizing relay 35 which raises relay blade 36 to the upper position shown in full lines, and opening the alarm circuit so that the bell ceases to ring.

Wesson relay 19 has two contacts 42 and 43 connected by wires 44 and 45 with the armature coil 46 of relay 29 and with the line between resistances 26 and 27 at 47.

Assuming that the system has been designed or adjusted to initiate an alarm with a change of oscillator energy sufficient to charge into or discharge from series capacitor 18, two or more micro-amperes, the indicator 23 of Wesson relay 19 will contact one or the other of contacts 42 or 43. When either of contacts 42 or 43 is thus contacted by indicator 23, a circuit is established from the + side of main power battery 9, through wire 24, bell test button 25, resistance 26, point 47, coil 46 of relay 29, wire 45, one or the other of contacts 42 or 43, indicator 23 of Wesson relay 19, wire 48, Day-Night switch 49, wire 50 and wire 7 to the - side of battery 9. The closing of this circuit energizes relay 29 and moves its blade 28 to open position shown at 28a in dot-dash lines, thus opening the control circuit for the alarm means 14.

When the control circuit for the alarm means 14 is thus opened it is de-energized, de-energizing relay 35 which drops blade 36 to position 36a closing the alarm circuit and ringing bell 33.

When the alarm has been triggered in this manner by

operation of Wesson indicator 23, the system may be placed back in normal operation by actuation of reset button 51 to reset the indicator 23 and blade 28 to the positions shown in full lines in the drawing.

The Day-Night switch 49 is closed for night operation to place the alarm device in operation and is open for day operation so as to prevent energizing relay 29 upon contact of indicator 23 with either of contacts 42 and 43 when the alarm system is intended to be inoperative.

If desired, a Mil-Amp meter 52 may be placed in the line 7 for determining power flow at various times during the operation of the system.

In installing the alarm system, its sensitivity may be adjusted to the desired amount by adjusting a variable resistor 53 connected with capacitor 54 and to the ground and also to the signal means circuit at 55. This sensitivity adjustment may also be accomplished by installing a resistor 53 of selected value.

The system requires no other adjustment for installation, setup and operation. It is self-correcting as far as all internal temperature or transistor characteristics or voltage shifts are concerned. One outstanding advantage of the system is that only one transistor 10 is required or used. This minimizes component failure and the amount of circuitry required.

As indicated, the sensitivity may be adjusted on installation and such adjustment may be made so that actual contact with the protected object 1 is required to trigger the alarm; or movements of an intruder at a distance of say one to two feet with respect to the protected object 1, or the single wires 2 and 12, may trigger the alarm. The entire system may be housed in a single compact unit located at any desired place and connected by a single wire 2 with the protected object. Alternatively, the monitoring means and alarm means may be remotely installed with respect to the signal means and protected object with a single wire 12 connection between the signal means and the monitor means.

Alternatively, the alarm system may be monitored remotely by utilizing an RF amplifier at the monitor means 40 retuned to the same frequency as the RF energy supplied by the signal means circuit to single wires 2 and 12.

The improved capacity alarm device may be used in conjunction with any existing alarm systems, such as local, central station and police alarms. Thus, the device instead of operating the bell 33 may be connected into such existing alarm systems.

Furthermore, instead of operating a bell, the device may be used to actuate any other type of signalling device, or illuminating device, as well as any desired machinery, motion picture camera, or tape recorder, etc.

The wire 2 connected between the signal means and the protected objects, in the alternative, may be connected with sensitive screens placed under rugs or floors or in walls or ceilings or over doors or windows to serve as an intrusion detection device with such screens or other sensing elements either visible or completely concealed.

The new capacity alarm device may be connected with the protected object at all times. When it is desired to render the alarm device inoperative, say during the daytime, the Day-Night switch 49 is moved to "Day" position so as to enable use of the protected object such as a safe 1 without triggering the alarm. The switch 49 may be moved to "Night" position at the end of the day to render the alarm device operative. Prior to such adjustment, if desired, the bell or other alarm signal may be tested by actuating the bell test button 25 in the manner described.

When the alarm system is set for protective use by moving switch 49 to "Night" position, the electromagnetic energy balance is reached in a few moments as the field is saturated around the protected object 1, around the single wire 2 leading from the protected object 1 to the signal means 4, and around the single wire 12 connected between the signal means 4 and monitor means

13. Any foreign object or body contacting the protected object 1 or single wires 2 or 12, or moving within the zone of one or two feet of any of these elements, depending upon the adjusted sensitivity of the system, will cause a change in the established electromagnetic field. 5 This change is reflected by current flow in the monitor means circuit resulting in a positive or negative swing of indicator 23 to contact either contact 42 or 43 which actuates the alarm circuit of alarm means 14 to operate the alarm.

10 In accordance with the invention, the "defeat" difficulty heretofore encountered with prior art devices is avoided in that the connection 12 between the signal means and monitor means is protected and not subject to defeat. Heretofore, in prior alarm systems, defeat measures could be applied to the two-wire connection previously required or used between the signal means and the monitor means.

15 Thus, the improved device protects all major components of the system, that is, the protected device 1, the single wire 2 connected with the signal means 4, the signal means itself, and the single wire 12 connected to the monitor means.

20 One of the fundamental aspects of the invention is the protection of the line 12 between the signal means 4 and the monitor means 13 coupled with the construction of this line with one single wire.

25 A further important aspect of the invention is the simplification of the system by utilizing only one transistor in the signal means.

30 A further important advantage of the new system is the ability to adjust the capacity balance to ground on installing the device by the selection of the desired resistance value for resistor 53 so as to impart the desired sensitivity to the device without necessarily insulating the protected object from the floor or surrounding metal objects. In addition, since the improved device is not affected by temperature changes, etc. it is completely foolproof in operation under all conditions.

35 Accordingly, the new capacity alarm system of the present invention is greatly improved over prior systems, is completely transistorized with controllable sensitivity, has reliability, protects more of the system circuitry with a more simplified and less costly construction than prior devices, and achieves many advantages not present or achieved in or by prior known systems or devices.

40 As indicated, the entire system may be housed as a single compact unit, such as in a metal cabinet 56 (FIG. 2) having a cover or door 57 and locked with a lock 58. When the components of the system illustrated in FIG. 1 are housed in a cabinet 56, the lock 58 may be opened with an authorized key by authorized personnel for inspection and testing of the components without triggering the alarm. In such case, the authorized key must have an insulated handle such as a plastic or wood handle.

45 In accordance with an established practice for controlling and handling alarm devices, it may be required that the alarm device should be tested at selected intervals, such as once a day, for determining whether the power supply batteries are functioning or whether the alarm means is operating. Such requirements may be satisfied if the opening of the cabinet door 57, even for authorized operation with an authorized key, triggers the alarm when the device is set for protective operation.

50 Thus, upon opening the cabinet door 57 the alarm is triggered indicating proper functioning of the device. The failure to give an alarm, upon opening the door, indicates malfunctioning of the device, such as a low battery.

55 In order to achieve the additional control just described, the system may be provided with an automatically compensated tamper control switch generally indicated at 59 in FIGS. 3 and 4, the wiring for which is illustrated in FIG. 4. Switch 59 is preferably a single pole double throw switch held by the door in one position

when the door is closed and released by the door to move to its other position when the door is opened.

Switch 59 may be connected to the signal means circuit of FIG. 1 by connecting a branch line 60 to signal means circuit line 7 adjacent the — side of main power supply battery 9; by connecting a branch line 61 to signal means circuit point 55; and by introducing a resistance 62 between point 55 and the + side of battery 9.

Branch line 60 is connected to one pole 63 of control switch 59, while branch line 61 is connected to the other pole 64 of control switch 59. A high value capacitor 65 is connected between switch pole 63 and one end of switch blade 66, at 67; and a low value capacitor 68 is connected between pole 64 and the end of blade 66 at 67. Thus, when switch blade 66 contacts pole 63 the high value capacitor 65 is shunted out and when blade 66 contacts pole 64 the low value capacitor 68 is shunted out.

When the control switch 59 is added as a control device for the alarm system, its operation is as follows:

With the cabinet door 57 in the closed position of FIG. 2 switch 59 is held with blade 66 in contact with pole 63 shunting out heavy capacitor 65. When the door 57 is opened as illustrated in FIG. 3, switch 59 is released permitting blade 66 to swing to the dotted position shown in FIG. 4 in contact with pole 64 thus allowing discharged heavy capacitor 65 to charge from the main circuit momentarily unbalancing the main circuit and triggering the alarm. In order to cut off the alarm, it is then necessary to operate reset member 51 (FIG. 1) to reset the indicator 23 of the Wesson relay 19.

When the door 57 is opened as shown in FIG. 3, any adjustments to the equipment may be made, the batteries replaced or the variable resistor 53 may be adjusted to change the sensitivity of the device. When the door 57 is closed from the position of FIG. 3 to the position of FIG. 2, switch 59 is actuated by the door to move the blade 66 to a position contacting pole 63, thus discharging heavy capacitor 65 which is shunted out of the circuit. However, nothing happens to disturb the balance of the main signal means circuit as the low value capacitor 68 compensates the system at this time.

The tamper switch 59, operating as just described triggers the alarm at all times when the door is opened and when the system is set for protective operation. As an alternative, it may be desired to maintain capacity protection for the components of the alarm device at all times, even though not set for protective operation, so as to permit the protected safe 1 to be used during authorized daytime intervals without triggering the alarm, but so that opening of the cabinet door 57 at any time triggers the alarm. This may be accomplished after the cabinet door 57 is opened, by moving Day-Night switch 49 to "Day" position. This permits line 2 running to protected safe 1 to be disconnected at 3 and a dummy load connected to the system at point 3. Under such alternative arrangement the protected object 1 may be used for authorized purposes, without triggering the alarm, and yet the remaining components of the capacity alarm device are protected against tampering by the reclosure of switch 49 after disconnecting single line 2 from the system, and the subsequent closing of door 57.

As an alternative to the use of the Day-Night switch 49 of FIG. 1, a manually operated reset actuating cam means may be provided for indicator 23 of relay 19 as shown in FIGS. 5, 6 and 7.

A typical commercial Wesson relay 19 with its magnetic contacts 42 and 43 and indicator 23 has a reset member 51 which actuates movable finger positioning members 69 and 70.

The normal position of finger members 69 and 70 is shown in FIG. 7 permitting the indicator 23 to swing in either direction and contact either of the magnetic contacts 42 or 43. When the reset member 51 is normally operated to actuate the fingers 69 and 70 to centrally posi-

tion indicator 23 as shown in FIG. 6, fingers 69 and 70 are in the position there illustrated confining indicator 23 to a central position while the system balances.

In accordance with this aspect of the invention, a manual reset control cam 71 is provided, rotatable on axis 72, and operated by a finger hole or knob 73. The cam 71 preferably is formed of an insulating material such as a plastic. The cam 71 preferably is shaped cylindrically at 74 throughout a portion of its periphery and has two cam lobes 75 connected by surfaces 76 with the cylindrical portion 74. The two lobes 75 are connected with each other by a raised curved surface portion 77, which is spaced a greater radial distance from the cam center 72 than the cylindrical surface 74.

When the cam 71 is in the position shown in FIG. 7, it is inoperative to engage reset member 51. This may be termed the cam "Night" position with the relay indicator 23 unobstructed in movement so that indicator 23 may respond to current changes in the monitor means circuit.

When the cam 71 is moved to the position of FIG. 5, cam surface 77 engages reset member 51 holding it sufficiently depressed to locate positioning arms 69 and 70 at intermediate positions which block full swinging movement of relay indicator 23, even though energized and which otherwise would result in the indicator 23 contacting either of contacts 42 or 43.

Thus the cam position of FIG. 5 may be termed a "Day" position for cam 71 since it holds relay indicator 23 from actuating the alarm circuit, even though indicator 23 is energized by current flow in the monitor means.

Cam means 71 has a third or intermediate position as shown in FIG. 6 where one or the other of lobes 75 fully depresses reset member 51 to centrally position relay indicator 23 whenever the cam 71 is moved from "Day" to "Night" position or vice versa. When control cam 71 is used, as described, for Day-Night and reset operations, the Day-Night switch 49 may be omitted from the system shown in FIG. 1. Thus, the Day-Night positions of cam 71 correspond to Day-Night positions of switch 49.

Accordingly, the new capacity alarm system of the present invention provides further protective means in that it may include devices for triggering the alarm at any time when the cabinet which houses one or more of the system components is open; and in that the entire system can be protected against tampering at all times, even during those periods when the protected object 1 may be disconnected.

In the foregoing description, certain terms have been used for brevity, clearness and understanding, but no unnecessary limitations are to be implied therefrom beyond the requirements of the prior art; because such words are used for descriptive purposes herein and not for the purpose of limitation and are intended to be broadly construed.

Moreover, the invention is not limited to the exact circuitry arrangement illustrated because the particular arrangement may be varied to provide other structural embodiments without departing from the scope of the present invention.

Having now described the features, discoveries and principles of the invention, the construction, operation and use of the improved capacity alarm system, and the advantageous, new and useful results obtained thereby; the new and useful systems, devices, apparatus, constructions, parts, elements, combinations and arrangements, and mechanical equivalents obvious to those skilled in the art, are set forth in the appended claims.

I claim:

1. In an electronic alarm circuit, a relay for actuating the alarm circuit, reset means for the relay, and a rotatable manually operable cam means engageable with the reset means movable to normal, reset and intermediate positions; said normal cam position permitting disengagement of the reset means from the relay, said reset cam position moving the reset means to engage and reset the

relay, and said intermediate cam position actuating the reset means to engage and hold the relay against actuation of the relay upon energizing the relay.

2. A capacity alarm system for a protected object including signal means forming a source of RF energy, monitor means, alarm means actuated by the monitor means, a first single wire connecting the signal means and protected object, a second single wire connecting the signal means and monitor means, and the signal means establishing a field of RF energy around the protected object and said first and second single wires, whereby entry of an intruder into said field causes current flow in the monitor means which actuates the alarm means, the alarm means including a normally de-energized alarm circuit, a relay in the monitor means actuated by current flow in the monitor means to energize the alarm circuit, reset means for the relay, and a rotatable manually operable cam engageable with the reset means and movable to normal, reset and intermediate positions, said normal cam position permitting disengagement of the reset means from the relay, said reset cam position moving the reset means to engage and reset the relay, and said intermediate cam position actuating the reset means to engage and hold the relay against actuation of the relay upon current flow in the monitor means.

3. A capacity alarm system for a protected object including a power supply, signal means forming a source of RF energy, monitor means, alarm means actuated by the monitor means, a first single wire connecting the signal means and protected object, a second single wire connecting the signal means and monitor means, and the signal means establishing a field of RF energy around the

protected object and said first and second single wires, whereby entry of an intruder into said field causes current flow in the monitor means which actuates the alarm means, a cabinet housing the signal, monitor and alarm means, a door upon the cabinet, means for disengaging the first single wire connecting the signal means and protected object, and means for actuating the alarm means upon opening the door, said last named means comprising a capacitor and a resistor connected in series across the power supply, and a switch normally shunting the capacitor when the door is closed, said switch being released when the door is opened so as to insert the capacitor into series with the resistor and allowing the discharged capacitor to charge so as to momentarily change the system voltage, the change in voltage affecting the signal means which in turn affects the monitor means and actuates the alarm means whereby the system is protected at all times against tampering whether or not the system is set for security protection of the protected object.
